UNITED STATES PATENT OFFICE.

ARTHUR G. RAYCRAFT, OF CARSON, NEVADA.

RULING-PEN.

SPECIFICATION forming part of Letters Patent No. 633,660, dated September 26, 1899.

Application filed July 27, 1898. Serial No. 686,996. (No model.)

To all whom it may concern:

Be it known that I, ARTHUR G. RAYCRAFT, a citizen of the United States, residing at Carson City, in the county of Ormsby and State 5 of Nevada, have invented certain new and useful Improvements in Ruling-Pens; and I do hereby declare the following to be a full, clear, and exact description of the invention, such as will enable others skilled in the art 10 to which it appertains to make and use the same.

My invention relates to improvements in ruling-pens such as are commonly used by draftsmen, and has for its objects to secure 15 a pen in which the points may be quickly and easily adjusted to form lines of any desired width, in which the inking part will yield a steady supply of ink to the pen-points, in which the ink may be changed from one color 20 to another without cleaning the entire pen, and in which other advantages of construction and operation will be obtained in a simple, effective, and economical manner.

In carrying out my invention I employ 25 means and devices which will be hereinafter described in detail and which are fully illustrated in the accompanying drawings, which form a part of this application, in which—

Figure 1 represents, partly in section, my 30 invention complete. Fig. 2 represents the same in a different position, and Fig. 3 is an enlarged detail of the ink-feeding device.

Like reference-numerals indicate like parts in the several views.

Referring to the accompanying drawings, 35 1 represents a metal cylinder of convenient size, which forms the body or handle of my improved ruling-pen. The ends of the cylinder are open, as at 1^a and 1^b, the former being at the handle or upper end and the latter at the lower or writing end of the instrument. The lower part of the cylinder is made tapering on opposite sides, as at 1^c and 1^d, and the other opposite sides are flattened to form 40 shoulders 2, as shown in Fig. 2. In these shoulders are pivoted the pen blades or points 3 3^a, the lower or ruling portion of which is formed in the usual manner with devices of this character; but the upper or pivoted 45 portions are rounded and provided with peripheral cogs 3^b. Below the cogged portion of the blades they are formed with a lug or

shoulder 3^c, the opposing faces of which are slightly curved and slant from the pivotal point inwardly and conform to the contiguous faces of the wedge or arrow-head shaped lug 10^b, to be described.

Rigidly secured to the shoulders 2 are round wires or rods 4, which extend downwardly between the blades 3 3^a and are bent inwardly, so as to lie closely together and overlap each other. Fitting snugly but removably over the wires or rods 4 are the ink retaining and delivering points 5, which are formed from thin metal strips, pointed and bent at their upper ends to form sockets for the wires. These points are of proper length to be normally in contact with the inner faces or sides of the blades 3 3^a, so that the ink on said points 5 will be delivered by gravity to 70 said blades in a well-known manner. The tubular form of said points enables them to hold a considerable supply of ink, which will be gradually fed to the blades or ruling points.

Extending longitudinally through the cylinder 1 is a solid rod or shaft 6, to the upper end of which is secured a button or thumb-screw 6^a, having a roughened or serrated periphery. Rigidly secured to or formed with 80 the button 6^a is a sleeve or cap 6^b, which fits loosely over the cylinder 1 and serves as a guide and support for said button. Secured to the shaft 6 is an annular washer 7, which slides loosely within the cylinder when the 85 shaft is moved longitudinally, and an annular shoulder 7^a, formed on the inside of the cylinder 1, limits the longitudinal movement of the washer 7 in the direction of said shoulder. The washer 7 forms a stop or an abutment for the upper end of a spiral spring 8, which surrounds the shaft for a portion of its length, and the opposite end of said spring 90 impinges against the annular shoulder 9, which is formed on the inside of the cylinder 1.

The lower end of the shaft 6 is threaded and enters the internally-threaded portion of a collar 10, which fits within the cylinder and is provided with cogs 10^a, which mesh with the cogs 3^b of the pen-blades 3 3^a, as shown in Figs. 1 and 2. To the threaded end of the shaft 6 is secured an internally-threaded arrow-head or wedge-shaped lug 10^b, against

the tapering sides of which rest the lugs 3^c when the pen-points are closed. It will be apparent that the downward movement of the lug 10^b will force outwardly the lugs 3^c, and thus cause the blades to turn on their pivotal point until they reach the position shown in Fig. 2, if desired. A very slight downward movement will be sufficient to separate the pen-points to form a wide line.

10 Surrounding the threaded end of the rod or shaft 6 is a small nut 10^c, which abuts against the end of the collar 10 upon the upward movement of the shaft, as shown in Fig. 1.

In the foregoing I have described the preferred manner of constructing my improved pen; but I do not wish to limit myself to the exact construction shown, as it is apparent that various modifications may be made in the shape and arrangement of parts and 20 some may be omitted without departing from the principles embodied in said invention.

In the operation of my ruling-pen a downward pressure on the button 6^a imparts a longitudinal movement to the shaft 6, which is 25 thereby communicated to the collar 10, which by the action of the teeth or cogs 10^a meshing with the teeth or cogs 3^b on the rounded ends of the blades 3 3^a revolves the latter pivotally, as shown in Fig. 2. The points 5^a are 30 then filled with ink, and by releasing the pressure on the button 6^a the blades 3 3^a are returned to their normal position by the action of the spring 8, which was compressed by said pressure, as clearly shown in Fig. 2.

35 If it be desired to separate the points or blades 3 3^a to make a wide line, the button 6^a should be turned instead of pressed downwardly. The turning will revolve the shaft 6, so that its threaded end will be pushed 40 along in the collar 10 and against the lug or wedge 10^b, which by pressing against the contiguous sides of the lugs 3^c will force them outwardly, and thus separate the points to the extent desired.

45 As the points 5 5^a are removably placed over the wires 4, other points carrying ink of a different color may be readily substituted therefor, thus avoiding the necessity of wasting the ink or entirely cleaning the pen every 50 time it is desired to change the color of the ink.

Having thus described my invention, what I claim as new, and desire to obtain by Letters Patent, is--

55 1. In a ruling-pen, the combination with a suitable handle, of ruling-pen points or blades pivoted to the handle and adapted to be adjusted by a shaft in said handle, removable

ink-feeding points contacting with the pen-points, and a shaft centrally located in said handle and engaging the inner end of said pen-points, said shaft having rotating and longitudinal movements for adjusting the pen-points, substantially as set forth.

2. In a ruling-pen, the combination with a suitable handle, of adjustable pen points or blades pivoted to the handle and adapted to be adjusted by a shaft in said handle, removable ink-feeding points, and a shaft located within the handle and engaging the inner end of the blades and adapted by a rotating movement to adjust said blades, substantially as set forth.

3. In a ruling-pen or like device, the combination with a suitable handle, of adjustable pen points or blades pivoted to said handle, ink-feeding points contacting with the pen-points, and a shaft located within the handle, engaging the inner end of the pen-points and adapted by its longitudinal and rotatory movements to adjust said pen-points, substantially as set forth.

4. In a ruling-pen, the combination with a suitable handle, of adjustable pen points or blades pivoted thereto and having cogged portions, and a shaft located within the handle and provided with cogs meshing with the cogs on the blades, for the purpose and substantially in the manner described.

5. In a ruling-pen, the combination with a suitable handle, of adjustable points or blades pivoted thereto and having cogged portions, a shaft located within the handle and provided with cogs meshing with the cogs on the blades, and also provided with a wedge-shaped lug, substantially as described.

6. In a ruling-pen or the like device, the combination with a suitable handle, of adjustable pen points or blades pivoted to the handle and having cogged portions, ink-feeding points, a shaft located within the handle having a cogged portion meshing with the like cogged portions of the pen-points and adapted by its longitudinal and rotatory movements to separate said points or blades, and a spring surrounding said shaft and adapted to normally close or bring together said points or blades, substantially in the manner and for the purpose described.

In testimony whereof I affix my signature in presence of two witnesses.

ARTHUR G. RAYCRAFT.
